DESIGN FOR A TOY BIRD

Calvin Rouse, Jamaica, N. Y.

Application July 25, 1946, Serial No. 131,903

Term of patent 7 years

(Cl. D34—15)

To all whom it may concern:

Be it known that Calvin Rouse, a citizen of the United States of America and resident of Jamaica, in the State of New York, has invented a new, original, and ornamental Design for Toy Bird, of which the following is a specification, reference being had to the accompanying drawing, forming part thereof, in which,

Fig. 1 is a perspective view of a toy bird embodying my new design,

Fig. 2 is a left rear perspective view thereof but of smaller size and with the wings in lowered position.

I claim:

The ornamental design for a toy bird, substantially as shown.

CALVIN ROUSE.
